The ornamental design for the analyte meter and strip port, as shown and described.

DESCRIPTION

FIG. 1 is a perspective view of an analyte meter, showing our new design,

FIG. 2 is a first side view of the analyte meter of FIG. 1,

FIG. 3 is a top view of the analyte meter of FIG. 1,

FIG. 4 is a second side view of the analyte meter of FIG. 1,

FIG. 5 is a bottom view of the analyte meter of FIG. 1,

FIG. 6 is a front view of the analyte meter of FIG. 1,

FIG. 7 is a rear view of the analyte meter of FIG. 1,

FIG. 8 is a perspective view of a strip port, showing our new design,

FIG. 9 is a first side view of the strip port of FIG. 8,

FIG. 10 is a top view of the strip port of FIG. 8,

FIG. 11 is a second side view of the strip port of FIG. 8,

FIG. 12 is a front view of the strip port of FIG. 8; and,

FIG. 13 is a rear view of the strip port of FIG. 8.
